UNITED STATES PATENT OFFICE.

ARCHER EDWARDS AND RICHARD JOHN EDWARDS, OF LONDON, ENGLAND.

MACHINERY OR APPARATUS FOR CUTTING PAPER OR OTHER SUBSTANCES INTO SHEETS.

SPECIFICATION forming part of Letters Patent No. 473,731, dated April 26, 1892.

Application filed June 8, 1891. Serial No. 395,531. (No model.) Patented in England January 7, 1889, No. 286.

To all whom it may concern:

Be it known that we, ARCHER EDWARDS and RICHARD JOHN EDWARDS, subjects of the Queen of Great Britain, residing at London, 5 in the county of Middlesex, England, have invented a new and useful Improvement in Machinery or Apparatus for Cutting Paper or other Substances into Sheets of Uniform Size, (for which we have obtained a patent in 10 Great Britain, No. 286, dated January 7, 1889,) of which the following is a specification.

Our invention relates to improvements in machines for cutting into sheets of any desired size rolls of emery or glass cloth or paper or for cutting up paper or card-board or other substances; and it consists of the novel features herein described and claimed.

Reference is had to the accompanying drawings, in which—
20 Figures 1 and 2 are side views of the entire machine, parts being omitted in Fig. 2. Fig. 3 is a view from below, and Fig. 3^a an end view, of a circular cutter and the method of adjusting it. Figs. 4 and 4^a are cross-sections 25 of one form of reversible cutting-knife. Figs. 5, 5^a, and 6 are detailed views of circular cutters. Fig. 7 is a detailed view of an adjustable friction-brake upon the toothed wheel, by which the feeding forward of the material 30 is effected.

Similar letters and figures refer to similar parts throughout the several figures.

a is a frame, preferably of cast-iron, in the upper part of which is arranged a transverse 35 shaft *b*, which can be set in revolution by a belt *d*, passing round a driving-pulley and kept tight by means of a movable pulley *c*, which can be pressed against the moving belt or removed from it, as desired, by means of a 40 lever or handle *e* for the purpose of starting or stopping the machine.

Across the upper part of the machine, at a sufficient distance above the transverse shaft *b*, we arrange a transverse lever or frame *f*, 45 carrying a cutting-knife *g*. This lever is of considerable weight, and it is pivoted at one end upon a transverse pivot or center *h*, turning upon the points of adjustable steel screws *i i'*, carried by the frame of the machine. The 50 other end of the heavy knife-lever *f* rests upon a cam *k*, driven by the shaft *b* and

toothed wheels *l l'*, with or without the intervention of a friction-roller. The cam *k* is so formed that it raises the heavy knife-lever *f* and blade *g* gradually and then allows them 55 to fall suddenly, the free end of the lever falling upon a block or buffer of india-rubber or other soft or elastic material.

Upon the upper part of the frame *a* is arranged a horizontal table, upon which the material to be cut is fed forward under the movable knife-blade *g*, and immediately under the latter the material passes over a fixed knife-blade *m*, past the edge of which the falling blade falls in the manner of shears, so 60 as to instantaneously cut the material transversely. A vertical guide *n* is fixed to the frame of the machine and guides the outer end of the knife-lever *f* as it falls, with the intervention of a friction-roller *o* upon the 65 lever, the guide being preferably slightly inclined, so that the lever falls freely at first, but toward the end of its stroke is brought close against the fixed knife-blade, so as to make a clean cut.

In order to feed forward the material upon the table, it is passed between horizontal rollers *r r'*, revolving in bearings upon the frame of the machine. These rollers are preferably covered with leather or india-rubber, and the 70 lower one *r'* revolves in bearings upon the pivoted frame *t*, which is pressed up with sufficient force by an adjustable weighted lever *u v* in the lower part of the machine. The upper roller *r* is set in revolution by means of a 75 toothed wheel *w²*, gearing with an intermediate toothed wheel *w'*, which is itself driven by a toothed wheel *w* upon the cam-shaft, already described. This last toothed wheel *w* has the teeth removed from a sufficient part 80 of its circumference in such a position that when the material has been fed forward upon the table into exactly the proper position to be cut transversely the part of the wheel *w* which is devoid of teeth comes opposite to the 85 intermediate wheel *w'*, which accordingly ceases to revolve and the material remains stationary. At this moment the movable knife-blade *g* falls and cuts the material, and the knife-blade is then raised again by the 90 cam *k*. As soon as it is high enough the toothed part of the wheel *w* comes into gear 95

with the intermediate wheel w' and the rollers $r r'$ are again set in motion and the material fed forward, and so on continuously. The material is supplied to the apparatus in the form of a roll s , of sufficient length, upon a movable axle turning in bearings in the frame of the machine or in a separate frame. In order to determine the exact length of the pieces to be cut in the manner described, we 5 make the axle or stud which carries the intermediate toothed wheel w' described adjustable in position, so that the teeth upon the driving-wheel w may come into or out of gear with its teeth somewhat earlier or later, 10 as may be desired, the movement of the rollers and the extent to which the material is fed forward being slightly varied accordingly. If the wheel w' is withdrawn from the wheel w so far that only the points of the teeth upon 15 the two wheels come into gear together, then when the space upon the wheel w which is free from teeth is reached during its revolution it comes more quickly out of gear with the wheel w' than if the teeth were deeply in gear and the wheel w' moves the feeding-rollers $r r'$, which it drives, for a proportionately shorter distance and the length of the sheet cut is slightly reduced. An extremely accurate adjustment for this purpose is obtained 20 by making the stud by which the wheel w' is carried adjustable in position, the stud being carried by a sliding piece working in the guide or slide x , which is pivoted to the frame of the machine at x' . By turning the screw y 25 the sliding piece and stud, together with the wheel w' , can be exactly adjusted, so that the teeth of the latter come into gear with those of the wheel w to a depth exactly necessary for the precise length of sheet which is to be 30 cut. By the vertical screw y' the position of the pivoted slide x can be accurately adjusted and fixed, so that the teeth of the wheels w' and w^2 always remain properly in gear, a support of the necessary thickness being placed 35 below the outer end of the slide x .

Where the material is to be divided longitudinally as well as cut transversely in the manner described, we arrange two steel cutting-disks $z z'$ one above and one below the 40 material. These disks are arranged upon horizontal transverse axles, their side faces being in contact with each other in the proper position in the width of the material, so that when in revolution they act as circular shears or cutters. The upper disk z is driven by 45 toothed wheels $1 2 2^a$, one of which is fixed upon the axle of the roller r , and the lower disk z' is fixed upon a spindle which turns upon conical steel points, the position of which 50 can be accurately adjusted endwise by means of adjusting-screws, so that the disk is adjusted transversely, as shown in Fig. 3 in plan, its bearings being carried in a frame 3, which 55 slides in transverse guides 4, carried by the frame, and the position of which is adjustable by the screws 5, 5, and 5^a . By means of the

hand-screw 5^a the whole frame 3 is moved bodily in the guides 4, while the adjustment in the frame for wear in the journals is made by the screws 5.

A piece of india-rubber or other elastic material is used at 6, by which the cutters are kept pressed together laterally.

8 is a guiding plate or board under which the sheet to be cut passes.

In order that the cutting-disks may retain the sharpness of their edges, we make an annular recess or groove 15 in the face of each, which is in contact with the other one, the recess or groove leaving an annular rib exterior 80 thereto and being at such distance from the edge of the disk that the annular rib of the opposite disk somewhat overlaps it, (the said groove), as shown in Fig. 5. In this way the only parts of the disk which are in contact 85 are the annular ribs outside the grooves or recesses, and we find that in this way the disks continue sufficiently sharp to cut well for a long time without sharpening.

Instead of disks having recesses, as described, we may use steel tubes of sufficient length, diameter, and thickness, as illustrated in Fig. 6. We arrange two of such tubes 10 and 11 end to end in such manner that the square end of each overlaps the other for a short distance in the manner described when the recessed disks are used. The tubes are fitted upon metal or other revolving mandrels or centers 12. The tubes are fixed by screws 16 or other means, and they may be arranged 100 so that as their cutting ends wear they can be brought forward upon their mandrels. In this way the cutting-edges will last for a long time before it is necessary to substitute fresh tubes.

The cutting devices described may be used for other purposes as well as for cutting the materials longitudinally in the machine—as, for instance, for cutting sheets of paper, cloth, or other material. The intermediate toothed wheel w' is provided with a rubber washer 13, which is pressed against by the nut 14, and so acts as an adjustable friction-brake, as illustrated in Fig. 7, by which its momentum is prevented from carrying the movement of 115 the feed-rollers too far.

In Fig. 7, w' is the toothed wheel carried upon a stud or center, but prevented from turning too freely by a washer or disk of felt or cloth 13, which can be tightened against the wheel w' , as desired, by the nut 14. The material is fed forward to the transverse cutting-knife under an adjustable guide-board, the lower side of which may be faced with steel, and the material after being cut into 125 sheets of the exact size required is pushed forward upon a delivering table or chute, from which it is removed at intervals.

In a convenient position in the machine we arrange a counting device 9, Fig. 1, of the ordinary well-known kind, which is operated by any of the moving parts. We prefer to con-

nect a bell 9^a with this counter, so that when a certain number of sheets have been delivered an audible indication is given.

It is evident that by using a sufficient number of cutting-disks the material may be divided longitudinally into three or more parts instead of two only.

The fixed and movable cutting-knives *m* and *g* are preferably made of such section that when one edge is worn blunt the blade can be turned partly round and another edge brought into operation. The blades may be longitudinally channeled at their sides, as shown in Fig. 4, or each blade may consist of a central bar of iron or steel, rectangular in cross-section, as shown in Fig. 4^a, a blade of steel 7 7 being arranged upon two of its opposite sides and attached to it by screws, which also fix it in position. Each of these blades 7 7 can be removed and reversed when desired, so that all its four edges can be used in succession, the two blades providing eight edges, all of which can be used in succession before they are sharpened.

25 We do not confine ourselves to the precise form and arrangements of the several parts of the machine, which may be varied more or less to suit varying circumstances; but

What we claim is—

30 1. In a cutting-machine of the character described, the combination, with a frame and a driving-shaft set transversely thereon, of a cam driven by said driving-shaft, a reciprocating knife pivoted at one end to said frame and lifted at the other end by said cam, an adjustable inclined guide for said reciprocating knife, a fixed knife set in said frame and adapted to coact with said reciprocating knife, and means for bringing the material between said knives, substantially as described.

2. In a cutting-machine of the character described, the combination, with a transverse shaft, of the cam *k* on said shaft, a toothed wheel *w*, with teeth extending only partly around the periphery thereof, also on said shaft, an adjustable toothed wheel *w'*, meshing with said toothed wheel *w*, a toothed wheel *w*², meshing with said toothed wheel *w'*, and friction-rollers *r'* and *r* on the same shafts

with the said toothed wheels *w* and *w'* and *w*² driven thereby, substantially as and for the purposes described.

3. In a cutting-machine of the character described, the combination, with a transverse shaft, of the cam *k* on said shaft, a toothed wheel *w*, with teeth extending only partly around the periphery thereof, also on said shaft, an adjustable toothed wheel *w'*, meshing with said toothed wheel *w*, a pivoted frame carrying said toothed wheel and screws for adjusting said frame horizontally and vertically, and a toothed wheel *w*², meshing with said toothed wheel *w'*, and friction-rollers *r'* and *r* on the same shafts with the said toothed wheels *w* and *w'* and *w*² driven thereby, substantially as and for the purposes described.

4. In a cutting-machine of the character described, a reversible H-shaped knife-blade composed of a central rectangular bar and reversible rectangular plates secured on either side of said bar and lapping over the sides thereof, substantially as described.

5. In a cutting-machine of the character described, the combination, with a revolving cutting-disk *z*, held against axial movement, of an axially-adjustable disk *z'*, overlapping the edge of the said disk *z* and mounted upon adjustable conical bearings *5*, a frame *3*, adapted to be moved in the line of the axis of the disk *z'*, and guides *4* for the said frame, substantially as described.

6. In a cutting-machine of the character described, the combination, with a revolving cutting-disk *z*, held against axial movement, of an axially-adjustable disk *z'*, overlapping the edge of the said disk *z* and mounted upon adjustable conical bearings *5*, a frame *3*, adapted to be moved in the line of the axis of the disk *z'*, and guides *4* for the said frame, and a hand-screw *5^a*, and rubber buffer *6*, substantially as described.

In testimony whereof we have hereunto set our hands in the presence of two witnesses.

ARCHER EDWARDS.

RICHARD JOHN EDWARDS.
